[57] **CLAIM**

The ornamental design for a lid handle, as shown and described.

DESCRIPTION

FIG. 1 is a top plan view of a lid handle showing my new design (the bottom is flat and unornamented);

FIG. 2 is a side elevation view, the opposite side view being a mirror image thereof;

FIG. 3 is a front elevation view, the rear elevation view being a mirror image thereof; and,

FIG. 4 is a perspective view thereof.

The broken line showing a lid in FIGS. 1-4 is for illustrative purposes only and forms no part of the claimed design.
